TYPOGRAPHICAL COMPOSING MACHINE

Eric Gayter, Timperley, and Arthur Staniland Hayward, Altrincham, England, assignors to Linotype and Machinery Limited, London, England, a limited liability company of Great Britain

Application December 6, 1938, Serial No. 244,138
In Great Britain December 7, 1937

17 Claims. (Cl. 199—20)

This invention relates to typographical composing machines, such as those known under the registered trade-mark "Linotype."

In such machines matrices are released from magazines to pass through an assembler entrance for the purpose of being assembled in line, so that a type bar or slug may be cast thereagainst, and in some machines means are provided to set the assembler entrance into communication with the outlets of either of two superposed magazines, at the will of the operator and without moving the magazines, so that the assembly of characters of different fonts in one line is facilitated. One convenient arrangement of this kind at present in common use comprises a pivoted throat section associated with or forming part of the assembler entrance, and means for moving it about its pivot to establish connection between one or other of the two magazines and a fixed section of the assembler entrance.

The object of the present invention is to devise improved apparatus to achieve the effect indicated above. To this end there is contemplated an arrangement of two non-pivoted assembler entrance sections, each in register with the outlet of one magazine, associated and running together to a single series of conduits, in register with the assembler chutes, which are thus common to the matrices from both of the magazines. Arrangements of this kind heretofore proposed have involved the use of escapement actuating devices extending through the passages of the assembler entrance, which impose undesirable restrictions on the size of the matrices which can be passed through the entrance channels.

In order to meet this difficulty, according to the present invention the means which are adapted to serve as operative connections between the escapement actuating levers and the escapements of the upper magazine are arranged to extend temporarily through the lower section when it is desired to release matrices from the upper magazine. These means may themselves form part of the lower section, or may be attached to a movable part thereof, or may be arranged to extend through apertures formed by a movable part or parts of the walls of the section. Thus they may be in the form of closely adjacent pivoted lever members which normally form the lower wall of the said lower section, so that matrices released from the lower magazine slide over these levers to the assembler chutes. When, however, it is desired to release matrices from the upper magazine, each such lever member, appropriate to the character it is desired to release, upon being

operated, swings about its pivot and extends through an aperture in the upper wall of the lower section, to engage and actuate the appropriate escapement of the upper magazine, for example, through an escapement striker mounted beneath the upper section. Adjustable means are provided to associate the escapement actuating devices either with the escapements of the lower magazine or with the above-mentioned pivoted lever members for actuating the escapements of the upper magazine as desired.

The invention is hereinafter described with reference to the accompanying drawings in which

Figure 1 is a side elevation, partly in section, of one constructional form of the invention;

Figure 2 is a side elevation, similar to Figure 1, but showing the parts in a different operative position;

Figure 3 is a side elevation, partly in section, of an alternative constructional form of the invention; and

Figure 4 is a side elevation, similar to Figure 3, but showing the parts in a different operative position.

In the drawings the invention is illustrated as applied to a typographical composing machine provided with a column of, say, four magazines 1, 2, 3 and 4, movable up and down to bring any two adjacent magazines into operative positions.

Two fixed assembler entrance sections 5, 6 provided to register with the outlets of magazines in the operative positions extend along the full width of the magazines and are divided each by partition walls into a series of channels. These assembler sections are curved and run together into a single, substantially vertical portion 7 (preferably integral therewith), through which the partition walls also run, so that matrices released into either section 5 or 6 must pass through the channels of this substantially vertical portion 7 to the usual assembler channels below, which are in register therewith.

A substantially horizontal shaft 8 extending across the full width of the magazines beneath the lower section carries a block 9 in which are slidably mounted a series of J-shaped elements or strikers 10, each in line with the escapement of a magazine channel. These J-shaped strikers 10 are normally urged by springs (not shown) away from the magazine, and at their outer, curved ends 11 each is in contact with a pivoted escapement actuating lever 12, operable from, or under control of, the keyboard of the machine.

When any key is operated, the lever 12 forces its associated J-shaped striker 10 inwards and operates the corresponding escapement, (as shown by the dotted lines in Figure 1), to release a matrix into the lower assembler entrance section 6.

In a similar manner there are pivotally mounted on a substantially horizontal shaft 13 beneath the upper section 5, a series of curved striker levers 14, each associated with and adapted, when actuated, to operate an escapement of a channel in the upper magazine 1.

The portion of the lower wall of the lower section 6 adjacent to the magazine 2 is formed wholly or in part by a series of lever members 15 pivoted to a rod 16 extending between brackets at the outer ends of the rigid portion 17 of the section and extending across the full width of the magazine. These lever members 15 may each be of the same width as a magazine channel (so that when they rest in contact with one another they form a continuous surface), or may be mounted between rigid comb-like projections 18 from the rigid portion of the said lower wall. In the latter case, the free ends of the lever members (being the ends nearer to the magazine) are preferably T-shaped, the cross-limb being of the same width as an adjacent magazine channel. As illustrated in Figure 1, the free ends of the lever members 15 normally rest on a bar or rod 19 extending between the ends of the assembler entrance section, so that they provide together a continuous surface in alignment with the floors of the magazine channels, and if their weight is not sufficient normally to move and hold them in such positions, light springs may be provided for that purpose. It will be clear that in this normal position the lever members 15 form a lower wall for the lower section, over which matrices released from the lower magazine 2 can slide.

Each of said lever members 15 has a short downwardly projecting limb 20 adjacent to the end of the shorter limb 21 of one of the aforementioned J-shaped strikers 10. The block 9 carrying the J-shaped strikers 10 is pivotally movable about the axis of its shaft 8, but when it is in a position suitable to allow the J-shaped strikers to operate the lower magazine escapements, the shorter limbs 21 of the J-shaped strikers 10 do not engage with the corresponding downwardly projecting limbs 20 of the lever members 15 during the fore-and-aft sliding movement of the strikers. When, however, it is desired to release matrices from the upper magazine 1, the block 9 carrying the J-shaped strikers 10 is moved about its pivot, so that such engagement with the lever members 15 occurs as the J-shaped strikers 10 are caused to slide towards the magazine. Such adjustment moves the longer limbs 22 of the J-shaped strikers out of their engaging position in relation to the escapements of the lower magazine.

The upper wall 23 of the lower section 6 is slotted or apertured at 24 to allow the above-mentioned lever members 15 to project therethrough when swung about their pivot (Figure 2), and from the above description it will be clear that when the J-shaped strikers 10 are positioned to release matrices from the upper magazine 1, the actuation of a key effects a sliding movement of the appropriate J-shaped striker 10 which engages the corresponding lever member 15 and swings it about its pivot, so that it projects through the slot or aperture 24 in the upper wall 23 of the lower section 6.

and engages one of the curved striker levers 14 beneath the upper section 5, thereby actuating the striker lever 14 and releasing the corresponding matrix escapement to allow passage of a matrix. To change over for the purpose of releasing matrices from the lower magazine, the only adjustment necessary is to turn the J-shaped strikers 10, and the block 9 carrying them, about their pivotal axis to a position suitable for that purpose, the lever members 15 and the upper 10 escapements in these circumstances remaining inoperative. The positions of the block 9 carrying the J-shaped strikers 10 may be determined by stops and/or a spring detent, if desired, and the adjustment may either be directly by hand, or by power-operated means under key or like control.

According to the constructional form of the invention illustrated in Figures 3 and 4, the push rods 25 operating the upper magazine escapement striker tappets 14 are held laterally in a comb pivoted in the upper assembler entrance side plates, allowing the push rods 25 to be swung to the position shown in Figure 4, leaving the lower throat 6 clear for operating the lower magazines.

The push rods 25 are moved upwards by levers 26 mounted on a rod 27 on which they are free to turn. The lever 26 is operated by the rocker lever 28 mounted free to turn on the rod 29. The rods 27 and 29 are carried in a slotted frame 30 that pivots on trunnions 31. The changing of escapement operation is effected by swinging the frame 30 into the respective operating positions.

The lower magazine escapement push rods 32 are mounted in a comb and held in place by a keep plate.

Figure 3 shows the mechanism set to operate the upper magazine escapement.

The striker lever 12 on being actuated, turns the rocker lever 28 anti-clockwise by the engagement of the projection 36 with the lower leg 37 of the rocker lever 28, thereby actuating the lever 26 to lift the push rod 25, rotating tappet 14 to operate the escapement of the upper magazine. To operate the lower magazine escapement, the push rods 25 are swung to the position shown in Figure 4 when the lever 33 operates the sliding shutter 34, closing the opening through which the levers 26 protruded. The striker mechanism is withdrawn by the link 35 swinging the frame 30 into the lower operating position as shown in Figure 4. The upper leg 38 of the rocker lever 28 will then coincide with the upper projection 39 of the striker lever 12. The rocker lever 28 is thus set to be actuated clockwise, engaging the lever 26 to lift the push rod 32 to operate the escapement of the lower magazine 2.

Having described our invention, we declare that what we claim and desire to secure by Letters Patent is:

1. In a typographical composing machine, the combination with a plurality of matrix magazines each provided with a set of escapements, of assembling mechanism including escapement actuating levers and an assembler entrance having two sections communicating with two superposed magazines and adapted to receive matrices discharged from the magazines, and lever members adapted to serve as operative connections between the escapement actuating levers and the escapements of the upper magazine arranged to extend temporarily through the lower section 75

when it is desired to release matrices from the upper magazine, said lever members normally occupying a retracted position and movable individually through the lower section by the operation of the corresponding escapement actuating levers.

2. In a typographical composing machine, the combination with a plurality of matrix magazines each provided with a set of escapements, of assembling mechanism including escapement actuating levers and an assembler entrance having two sections communicating with two superposed magazines and adapted to receive matrices discharged from the magazines, and lever members forming part of the lower matrix supporting wall of the lower section adapted to serve as operative connections between the escapement actuating levers and the escapements of the upper magazine arranged to extend temporarily through the lower section when it is desired to release matrices from the upper magazine, said lever members normally occupying a retracted position and movable individually through the lower section by the operation of the corresponding escapement actuating levers.

3. In a typographical composing machine, the combination with a plurality of matrix magazines each provided with a set of escapements, of assembling mechanism including escapement actuating levers and an assembler entrance having two fixed sections communicating with two superposed magazines and adapted to receive matrices discharged from the magazines, and lever members forming part of the lower matrix supporting wall of the lower fixed section so as to serve as operative connections between the escapement actuating levers and the escapements of the upper magazine arranged to extend temporarily through the lower section when it is desired to release matrices from the upper magazine.

4. In a typographical composing machine, the combination with a plurality of matrix magazines each provided with a set of escapements, of assembling mechanism including escapement actuating levers and an assembler entrance having two fixed sections communicating with two superposed magazines and adapted to receive matrices discharged from the magazines, and lever members pivoted to the lower rigid wall of the lower fixed section so as to be capable of extending upwardly through the lower section to serve as operative connections between the escapement actuating levers and the escapements of the upper magazine.

5. In a typographical composing machine, the combination with a plurality of matrix magazines each provided with a set of escapements, of assembling mechanism including escapement actuating levers and an assembler entrance having two fixed sections communicating with two superposed magazines and adapted to receive matrices discharged from the magazines, and means pivoted above the lower fixed section capable of extending downwardly through the lower section to serve as operative connections between the escapement actuating levers and the escapements of the upper magazine.

6. In a typographical composing machine, the combination with a plurality of matrix magazines each provided with a set of escapements, of assembling mechanism including escapement actuating levers and an assembler entrance having two fixed sections communicating with two superposed magazines and adapted to receive

matrices discharged from the magazines, and push rods pivotally mounted above the lower fixed section and capable of extending downwardly through the lower section to serve as operative connections between the escapement actuating levers and the escapements of the upper magazine.

7. In a typographical composing machine, the combination with a plurality of matrix magazines each provided with a set of escapements, of assembling mechanism including escapement actuating levers and an assembler entrance having two sections communicating with two superposed magazines and adapted to receive matrices discharged from the magazines, strikers through which the escapements of the lower magazine are operable, means for moving the strikers to a position to be engaged by the escapement actuating levers, and pivoted lever members actuated by the strikers and arranged to extend temporarily through the lower entrance section for releasing matrices from the upper magazine.

8. In a typographical composing machine, the combination with a plurality of matrix magazines each provided with a set of escapements, of assembling mechanism including escapement actuating levers and an assembler entrance having two sections communicating with two superposed magazines and adapted to receive matrices discharged from the magazines, strikers through which the escapements of the lower magazine are operable, means for moving the strikers to a position to be engaged by the escapement actuating levers, pivoted lever members actuated by the strikers, and curved strikers mounted beneath the upper section and engaged by the pivoted lever members to actuate the escapements of the upper magazine.

9. In a typographical composing machine, the combination with a plurality of matrix magazines each provided with a set of escapements, of assembling mechanism including escapement actuating levers and an assembler entrance having two sections communicating with two superposed magazines and adapted to receive matrices discharged from the magazines, strikers through which the escapements of the lower magazine are operable, a block in which the strikers are slidably mounted, means for turning the block to allow the strikers to be engaged by the escapement actuating levers, pivoted lever members actuated by the strikers, and curved strikers mounted beneath the upper section and engaged by the pivoted lever members to actuate the escapements of the upper magazine.

10. In a typographical composing machine, the combination with a plurality of matrix magazines each provided with a set of escapements, of assembling mechanism including escapement actuating levers and an assembler entrance having two sections communicating with two superposed magazines and adapted to receive matrices discharged from the magazines, J-shaped strikers through which the escapements of the lower magazine are operable, a block in which the strikers are slidably mounted, a pivotal mounting for the block whereby the block can be turned to allow the strikers to be engaged by the escapement actuating levers, lever members pivoted to the lower rigid wall of the lower section and actuated by the J-shaped strikers, and curved strikers mounted beneath the upper section and engaged by the pivoted lever members to actuate the escapements of the upper magazine.

11. In a typographical composing machine, the

- combination with a plurality of matrix magazines each provided with a set of escapements, of assembling mechanism including escapement actuating levers and an assembler entrance having two sections communicating with two superposed magazines and adapted to receive matrices discharged from the magazines, push rods pivotally mounted above the lower section capable of extending downwardly through the lower section, 5 strikers for actuating the escapements of the lower magazine, and rocker mechanism operable through the escapement actuating levers for actuating the pivotally mounted push rods or the escapement strikers.
12. In a typographical composing machine, the combination with a plurality of matrix magazines each provided with a set of escapements, of assembling mechanism including escapement actuating levers and an assembler entrance having two sections communicating with two superposed magazines and adapted to receive matrices discharged from the magazines, push rods pivotally mounted above the lower section capable of extending downwardly through the lower section, 10 strikers for actuating the escapements of the lower magazine, and rocker mechanism operable through the escapement actuating levers for actuating the pivotally mounted push rods or the escapement strikers.
13. In a typographical composing machine, the combination with a plurality of matrix magazines each provided with a set of escapements, of assembling mechanism including escapement actuating levers and an assembler entrance having two sections communicating with two superposed magazines and adapted to receive matrices discharged from the magazines, push rods pivotally mounted above the lower section capable of extending downwardly through the lower section, 15 strikers for actuating the escapements of the lower magazine, rocker mechanism comprising two mutually engaging rocker elements adapted to be moved into different operative positions relatively to the escapement actuating levers so as to actuate the pivotally mounted push rods or the escapement strikers of the lower magazine.
14. In a typographical composing machine, a combination according to claim 12, wherein the 20 rocker mechanism is mounted in a frame connected to the pivotal mounting for the push rods so that movement of the push rods to inoperative position moves the frame to allow the rocker mechanism to actuate the escapement strikers of the lower magazine.
15. In a typographical composing machine, the combination with a plurality of matrix magazines each provided with a set of escapements, of assembling mechanism including escapement actuating levers and an assembler entrance having two sections communicating with two superposed magazines and adapted to receive matrices discharged from the magazines, means pivoted above the lower section capable of extending downwardly through the lower section to serve 25 as operative connections between the escapement actuating levers and the escapements of the upper magazine, and means for closing the opening in the lower section when the push rods are in inoperative position.
16. In a typographical composing machine the combination as in claim 15, wherein a slidable shutter for the opening in the lower section is connected to the pivotal mounting for the push rods so as to close the opening when the push 30 rods are moved to inoperative position.
17. In a typographical composing machine, the combination with a plurality of matrix magazines each provided with a set of escapements, of assembling mechanism including escapement actuating levers and an assembler entrance having two sections communicating with two superposed magazines and adapted to receive matrices discharged from the magazines, curved strikers for actuating the escapements of the upper magazine, push rods engaging the curved strikers and mounted in a comb pivoted above the lower section, rocker mechanism mounted in an adjustable frame and adapted to be operated by the escapement actuating levers, a link connecting the 35 comb to the frame so that pivotal movement of the comb to bring the push rods into operative position moves the rocker mechanism into position for actuating the push rods, and a link connecting the pivoted comb to a slidable shutter 40 in the lower section so as to uncover the opening therein when the push rods are moved to operative position.
- ERIC GAYTER.
ARTHUR STANILAND HAYWARD. 50
